UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

SEWING-MACHINE.

1,361,871.

Specification of Letters Patent. Patented Dec. 14, 1920.

Application filed January 2, 1919. Serial No. 269,201.

To all whom it may concern:

Be it known that I, JOHN KIEWICZ, a citizen of the United States, residing at Boston, county of Suffolk, State of Massachusetts, have invented an Improvement in Sewing-Machines, of which the following description, in connection with the accompanying drawing, is a specification, like characters on the drawing representing like parts.

10 This invention relates to sewing machines and particularly to two-thread buttonhole sewing machines of that type which are equipped with a thread-trimming mechanism designed to cut the thread at the end 15 of the stitching operation on a buttonhole. Where the under thread is thus cut close to the work at the end of the stitching on a buttonhole, it is desirable that a sufficient length of under thread should be left protruding from the under thread mechanism so that when the stitching is started again 20 on another buttonhole the first stitch will be properly formed because if the thread end is too short, there is danger that it 25 will be pulled through the work in tightening the first stitch, thus making an imperfect stitch.

It is one of the objects of my present invention to provide a novel thread-pulling-off device which becomes operative automatically when the stitching on any buttonhole is completed to draw off from the source of supply a length of under thread before the thread is cut so that there will 30 be left protruding from the under thread mechanism the required length to insure the correct formation of the first stitch.

Another object of my invention is to provide a novel thread-pulling-off device which 40 is arranged to be actuated by the actuator that controls the thread-trimming mechanism, so that one actuator is sufficient to operate both the thread trimmer and the thread-pulling-off device.

45 Other objects of my invention are to improve generally thread-trimming and thread-pulling-off devices for buttonhole sewing machines, all as will be hereinafter set forth.

50 In order to give an understanding of my invention, I have illustrated in the drawings a selected embodiment thereof which will now be described, after which the novel

features will be pointed out in the appended claims.

55

In the drawings, Figure 1 is a side view of a buttonhole sewing machine embodying my invention;

Fig. 2 is a plan view of a part of the base frame with the clamps removed for the purpose of showing better the construction and operation of the pull-off device for the under thread;

Fig. 3 is an underside view of the bed plate showing the actuator for the pull-off and thread-trimming devices;

Figs. 4 and 5 are plan views of the clamp plate showing the operation of the thread trimmer and the pull-off device.

Since my invention relates particularly 70 to the means for pulling off the under thread and for cutting or trimming the thread, I have not deemed it necessary to illustrate herein a complete buttonhole sewing machine, but have contented myself 75 with illustrating a sufficient portion of the sewing machine to enable the invention to be understood.

1 indicates the bed plate of a sewing machine from which rises the head or overhanging arm 2 carrying the upper thread-handling mechanism which is herein shown in the form of a reciprocating eye-pointed needle 3 that is carried by the usual reciprocating needle bar 4.

80

The bed plate 1 carries the work-holding means which is herein shown in the form of the usual clamp plate 5 that is slidably mounted in ways 6 formed on the bed plate 1 and work clamps 7 which are pivotally 90 mounted on the clamp plate 5. Situated beneath the bed plate 1 is the under-thread-handling mechanism which is indicated generally at 8 and which may be of any suitable or usual type. In the type of sewing 95 machine herein shown this under-thread-handling mechanism is carried by a turret which is rotatably mounted in suitable bearings carried by the depending portion 9 of the frame, said turret sustaining at its upper end the throat-plate 10 which is provided with an aperture 11 through which the under thread 12 extends and through which the needle 3 passes when said needle descends through the work. The under 100 thread mechanism is provided with the

85

90

95

100

105

usual looper to take a loop of upper thread 13 upon each descent of the needle and is arranged to interlock the under thread 12 with the upper thread 13, all as usual in 5 two-thread buttonhole sewing machines.

The clamp plate 5 on which the work is clamped by the work clamps 7 is moved longitudinally of the ways 6 for feeding the work during the stitching operation and 10 also for the purpose of carrying the work from stitching to buttonhole-cutting position at the end of the stitching operation by means of the usual main cam indicated generally at 14, the connections between the 15 clamp plate and the main cam being such as are ordinarily employed in buttonhole sewing machines of this type.

The parts thus far described may have 20 any suitable construction but for illustrative purposes they are shown as having substantially the same construction as will be found in United States Letters Patent No. 1,188,944, dated June 27, 1916, or in my co-pending application Se. No. 203,899, filed November 26, 25 1917.

Buttonhole sewing machines of this type are usually constructed so that when they are set in operation the work clamps 7 are first closed onto the work *w* indicated in 30 dotted lines Fig. 1, thereby clamping the latter to the clamp plate 5, and the buttonhole cutter, if one is used, is actuated to cut the buttonhole after which the clamp plate is moved toward the front of the machine to 35 carry the work from buttonhole-cutting to stitching position. The stitch-forming mechanism is then set in operation and the stitching proceeds down one side of the buttonhole and back along the other side, the clamp 40 plate 5 being given the appropriate feeding movement to feed the work properly. At the end of the stitching operation on the buttonhole the sewing machine is brought to rest with the needle 3 raised and the work clamps 45 7 are then released to unclamp the work, after which the clamp plate is given a movement to carry the work from stitching to buttonhole-cutting position. After this 50 cycle of operations has been completed, the machine is brought to rest.

The sewing machine herein illustrated is provided with tread-trimming mechanism which is carried by the clamp plate 5 and operates to cut the under thread close to and 55 beneath the work when the stitch-forming mechanism comes to rest and the work is unclamped.

This thread-trimming device is somewhat 60 similar to that illustrated in my co-pending application, Se. No. 203,899, and comprises two thread-cutting jaws 15 and 16 which are pivotally connected together at 17 and are slidably mounted on the clamp plate 5. Each jaw has an inclined slot formed in 65 its rear end, said slots being indicated at

18 and 19, respectively, said slots receiving a pin 20 carried by a lever 21 which is pivoted at 22 to the clamp frame 5. The thread-cutting jaws are capable of bodily movement toward and from the throat-plate 10 and 70 are guided in their movement by a swinging arm 24, one end of which is pivotally connected to the pivotal pin 17 and the other end of which is pivoted to the clamp plate at 25. This arm 24 plays between two stops 75 23 and 53 which limit its swinging movement and thereby limits the reciprocating movement of the jaws. The thread-trimming devices are situated on the upper side of the clamp plate but occupy a position beneath the work *w* when the work is applied to the clamp plate. The thread-trimming devices normally occupy a retracted position shown in Fig. 4 during the stitching operation and are yieldingly held in such position 80 by means of a spring 26, which acts on a pin or projection 27 extending from the lever 21. The action of this spring 26 normally holds the pin 20 at the left-hand ends of the slots 18 and 19, as seen in Fig. 4, 85 90 whereby the jaws 15 and 16 are held in their open position. When the cutting jaws are in their retracted position they are situated in front of the throat-plate or stitching point, as shown in Fig. 4, and hence do not 95 interfere with the stitching operation. When the stitching on the buttonhole has been completed and the work-clamps 7 are released, the lever 21 is swung toward the 100 throat-plate and during the first part of the swinging movement of the lever, the open jaws 15 and 16 will be moved bodily toward the throat-plate until the arm 24 strikes the stop 23, at which time the cutting edges 28 of said jaws are situated over the throat-plate 10 so that the under thread and the 105 loop of upper thread that is retained by the looper will be situated between the cutting edges. Further swinging movement of the lever 21 will carry the pin 20 to the right-hand end of the slots 18 and 19, thus closing the cutting jaws and severing both the under thread and the loop of upper thread, as seen in Fig. 5. This form of thread-cutting device is substantially the same as that illustrated in my co-pending application Se. No. 203,899, above referred to. 110 115

The operative movement of the lever 21 is herein derived from an actuating lever 30 which is situated beneath the bed plate and 120 is pivoted to the frame at 31, said lever having at its outer end the upturned portion 32 which is situated to engage the tail 33 of the lever 21. The inner end 34 of the actuating lever 30 is adapted to be engaged by a roll 125 35 carried by an arm 36 which is rigid with the main cam 14. This main cam is provided with a hub 37 which depends through the cam housing 38 and to which the arm 36 is secured. The main cam 14 and conse- 130

quently the arm 36 make one complete revolution for each buttonhole, and the parts are so designed and timed that the roll 35 will actuate the lever 30 at the point in the cycle 5 of operations when the sewing on the button-hole has been completed and just as the work clamps 7 are released. The movement of the actuator 30 operates the lever 21 thereby to move the thread-trimming devices into 10 operative position and actuate them to trim the thread, as above described.

In order to pull off from the source of supply a sufficient length of under thread to provide for forming properly the first 15 stitch when the sewing machine is started in operation, I have provided a pull-off lever 39 which is pivoted at 40 on the end of the bed plate 1 and beneath the clamp plate 5. This pull-off lever 39 is acted upon by a pull- 20 ing spring 41 which normally holds it in its full line positions Figs. 2 and 4. The end 42 of the lever is situated close to the throat-plate 10 and is provided with a thread-engaging notch 43 and said lever is so shaped 25 and constructed that when it is swung from the full to the dotted line position, Fig. 2, the end 42 thereof will be carried beneath the throat-plate 10 and the notch 43 will be brought against the portion of the under 30 thread 12 leading from the under thread mechanism up through the throat-plate.

During the sewing operation, the pull-off lever 39 is in its retracted or full-line position, Fig. 2, but at the end of the stitching 35 operation and before the thread-trimming device is actuated to cut the thread, said lever is swung from its full to its dotted line position Fig. 2, during which swinging movement the notch 43 engages the under 40 thread 12 and draws off a length from the source of supply, it being understood, of course, that the thread is at this time connected to the work. Immediately after this 45 required length of under thread has been pulled from the source of supply, the thread-trimming device is actuated, as above described, to cut the under thread.

In order to simplify the mechanism, I have provided a construction wherein the 50 pulling-off movement of the pull-off lever 39 is effected by the actuating lever 30 so that said lever 30 operates both the pull-off lever and the thread-trimming device. For this purpose the pull-off lever 39 is 55 provided with the tail or extension 44 which normally extends beyond the tail 33 of the lever 21, the end of the extension 44 being formed with the cam surface 45 with which the upstanding part 32 of the lever 30 normally has engagement. Hence during the 60 initial movement of the actuating lever 30 the part 32 operates on the cam surface 45 thereby to swing the pull-off lever 39 from the full to the dotted line position and pull 65 off the required length of under thread from

the source of supply. The inner face or edge 47 of the extension 44 has such a shape that after the end 32 of the lever 30 has passed the corner 46, said lever can return toward its normal position under the influence of the spring 41 thereby letting up on the under thread. The relative position of the tail 33 of the lever 21 and the cam surface 45 of the extension 44 is such that the end 32 of the lever 30 will engage 70 the tail 33 immediately after it has passed the corner 46 so that as soon as the under thread has been pulled off and then the pressure of the pull-off on the under thread has been released, the thread-trimming device 75 is moved into position to engage the thread and then is actuated to sever the thread. The advantage derived from thus releasing the pull-off lever before the thread-trimming device is actuated is that there is no strain 80 on the under thread tending to draw the work down against the clamp plate when the thread-trimming device moves forwardly and hence there is no danger that the cloth will be cut by the closing movement of the 85 thread-cutting jaws.

I claim:

1. In a sewing machine, the combination with a frame, of stitch-forming mechanism carried by the frame and adapted to concatenate an upper and an under thread, 95 work-holding means constructed to hold the work clamped during the stitching operation, means to produce a relative work-feeding movement between the work-holding means and the frame carrying said stitch-forming mechanism, a thread-trimming device carried by the work-holding means and operating to cut the under thread beneath the work at the completion of the sewing 100 operation, a pull-off device mounted on said frame and adapted to pull off a length of under thread from the source of supply, and an actuator common to both devices.

2. In a sewing machine, the combination with a frame, of stitch-forming mechanism carried by the frame and adapted to concatenate an upper and an under thread, work-holding means constructed to hold the work clamped during the stitching operation, means to produce a relative work-feeding movement between the work-holding means and the frame carrying said stitch-forming mechanism, a thread-trimming device carried by the work-holding means 110 and operating to cut the under thread beneath the work at the completion of the sewing 115 operation, a pull-off device mounted on said frame and adapted to pull off a length of under thread from the source of supply, and an actuator common to both devices and arranged first to actuate the pull-off device 120 and then subsequently to operate the trimming device.

3. In a sewing machine, the combination 130

with stitch-forming mechanism for concatenating an upper and an under thread, of work-holding means, a main cam for producing a relative feeding movement between the stitch-forming mechanism and work-holding means, a thread-trimming device carried by the work-holding means, a pull-off device supported independently of the work-holding means and arranged to 5 pull off a length of under thread from the source of supply, an actuator constructed to actuate first the pull-off device and then the thread-trimming device, and means rigid with the main cam for operating said 10 actuator.

4. In a sewing machine, the combination with stitch-forming mechanism for concatenating an upper and an under thread, of work-holding means, a main cam for producing 20 a relative feeding movement between the stitch-forming mechanism and work-holding means, a thread-trimming device carried by the work-holding means for cutting the under thread beneath the work, a 25 pull-off device supported independently of the work-holding means and arranged to pull off a length of under thread from the source of supply, a lever adapted by its swinging movement to actuate first the pull-off and then the thread-trimming device, and means associated with the main cam for 30 actuating said lever.

5. In a sewing machine, the combination with work-holding means, of stitch-forming 35 mechanism for concatenating an upper and an under thread, a main cam for producing a relative feeding movement between the stitch-forming mechanism and work-holding means, a pull-off device adapted to pull 40 off a length of under thread from the source of supply, a thread-trimming device separate from the pull-off device, a pivotally-mounted actuating lever adapted during its turning movement first to actuate the pull-off device and then to operate the trimming device, and means associated with the main 45 cam to operate said lever.

6. In a sewing machine, the combination with a frame, of work-holding means movably mounted thereon, means to give said work-holding means a feeding movement, stitch-forming mechanism constructed to concatenate an upper and an under thread, a pull-off device mounted on the frame and adapted to pull off a length of under thread 55 from the source of supply, and a thread-trimming device carried by and movable with the work-holding means for cutting the under thread beneath the work at the 60 end of a sewing operation.

7. In a sewing machine of the type constructed to sew a short seam and then come to rest, the combination with a frame, of work-holding means movably mounted 65 thereon, means to give said work-holding

means a feeding movement, stitch-forming means constructed to concatenate an upper and an under thread, a pull-off device mounted on the frame and adapted to pull off a length of under thread from the source 70 of supply, a thread-trimming device for cutting the under thread beneath the work carried by the work-holding means, and means common to both devices to actuate them.

8. In a sewing machine of the type constructed to sew a short seam and then to come to rest, the combination with a frame, of work-holding means movably mounted thereon, means to give said work-holding means a feeding movement, stitch-forming 75 means constructed to concatenate an upper and an under thread, a pull-off device mounted on the frame and adapted to pull off a length of under thread from the source of supply, a thread-trimming device for cutting the under thread beneath the work carried by and movable with the work-holding means, an actuating lever common to both devices, and means to actuate said lever at 80 the end of a sewing operation.

9. In a sewing machine, the combination with a frame having a bed plate portion, of work-holding means slidably mounted thereon, a stitch-forming mechanism for concatenating an upper and an under thread 95 and including a throat-plate through which the threads pass, a pull-off device mounted on the bed plate to swing in a horizontal plane and adapted by its swinging movement to pull off a length of under thread, 100 said device having a cam surface, an actuating lever adapted by its swinging movement to wipe over said cam surface thereby to actuate the pull-off device and then to release the latter, and a spring to return the pull-off 105 device to normal position.

10. In a sewing machine, the combination with a frame having a bed plate portion, of work-holding means slidably mounted thereon, a stitch-forming mechanism including a throat-plate through which the threads pass, a pull-off member pivoted to the bed plate beneath the work-holding means and adapted to swing in a horizontal plane and by its swinging movement to pull off a length 110 of under thread, one end of said member projecting beyond the end of the bed plate, and an actuating lever pivoted to the frame and adapted to engage the projecting end of the pull-off member.

11. In a sewing machine, the combination with a frame having a bed plate portion, of work-holding means slidably mounted thereon, stitch-forming mechanism including a throat plate through which the 115 threads pass, a pull-off member pivoted to the bed plate beneath the work-holding means and adapted to swing in a horizontal plane and by its swinging movement to pull off a length of under thread, one end of 120 said member projecting beyond the end of the bed plate, and an actuating lever pivoted to the frame and adapted to engage the projecting end of the pull-off member.

said member projecting beyond the end of the bed plate, a thread-trimming device carried by the work-holding means, and an actuating lever pivoted to the frame and adapted 5 by its swinging movement to engage the projecting end of the pull-off lever thereby to actuate the latter and then to actuate the thread-trimming device.

12. In a sewing machine, the combination 10 with stitch-forming mechanism for concatenating an upper and an under thread, of work-holding means for holding the work clamped during the stitching operation, means to produce a relative feeding movement between the stitch-forming mechanism and the work-holding means, a thread-trimming device carried by the work-holding means and operating to cut the under thread beneath the work at the completion of the 15 stitching operation, a pull-off device adapted to pull off a length of under thread from the source of supply and supported so that there is a bodily relative movement between it and the trimming device during the work- 20 feeding movement, and an actuator common to both devices.

13. In a sewing machine, the combination 25 with stitch-forming mechanism for concatenating an upper and an under thread, of work-holding means for holding the work clamped during the stitching operation, means to produce a relative feeding movement between the stitch-forming mechanism and the work-holding means, a thread-trimming device carried by the work-holding 30 means and operating to cut the under thread beneath the work at the completion of the stitching operation, a pull-off device adapted to pull off a length of

under thread from the source of supply 40 and supported so that there is a bodily relative movement between it and the trimming device during the work-feeding movement, and an actuator common to both devices, and arranged to actuate first the pull-off device 45 and then to operate the trimming device.

14. In a sewing machine, the combination with a frame, of work-holding means movably mounted thereon, means to give said work-holding means a feeding movement, 50 stitch-forming mechanism constructed to concatenate an upper and an under thread, a pull-off device mounted on the frame and adapted to pull off a length of under thread from the source of supply, and a thread-trimming device carried by and movable with the work-holding means for cutting the under thread beneath the work at the end of the sewing operation. 55

15. In a sewing machine of the type constructed to sew a short seam and then come to rest, the combination with a frame, of work-holding means movably mounted thereon, means to give said work-holding means a feeding movement, 60 stitch-forming means constructed to concatenate an upper and an under thread, a pull-off device mounted on the frame and adapted to pull off a length of under thread from the source of supply, a thread-trimming device carried by the work-holding means and adapted 65 to cut the under thread beneath the work, and means common to both devices to actuate them. 70

In testimony whereof I have signed my name to this specification. 75

JOHN KIEWICZ.
